(57) CLAIM

The ornamental design for a gift box, as shown and described.

DESCRIPTION

FIG. 1 is a front, left, and top perspective view of a gift box showing the new design;

FIG. 2 is a front view thereof;

FIG. 3 is a rear view thereof;

FIG. 4 is left side view thereof;

FIG. 5 is a right side view thereof;

FIG. 6 is a top view thereof; and,

FIG. 7 is a bottom view thereof.

The broken line showing is for the purpose of illustrating portions of the gift box and forms no part of the claimed design.
